US00D778667S

(12) **United States Design Patent** (10) **Patent No.:** **US D778,667 S**
Casper et al. (45) **Date of Patent:** **** Feb. 14, 2017**

(54) **VENTURI DEVICE**

(71) Applicants: **Thomas J Casper**, Waukesha, WI
 (US); **Jeffrey Casper**, Minneapolis, MN
 (US)

(72) Inventors: **Thomas J Casper**, Waukesha, WI
 (US); **Jeffrey Casper**, Minneapolis, MN
 (US)

(**) Term: **15 Years**

(21) Appl. No.: **29/530,931**

(22) Filed: **Jun. 22, 2015**
